WRAPPING MACHINE

Wilhelm B. Bronander, Montclair, N. J.

Application December 12, 1941, Serial No. 422,712

8 Claims. (Cl. 93—1)

This invention relates to wrapping machines and particularly to mechanism for feeding and cutting the wrapper strip and tear strip.

The invention has for its salient object to provide a machine for efficiently and accurately feeding and cutting a wrapper strip and tear strip.

Another object of the invention is to provide a machine of the character described, so designed as to feed, cut and apply the wrapper and tear strip to the article to be wrapped in such a manner that the tear strip can be easily grasped and will operate effectively to sever the wrapper.

Further objects of the invention will appear from the following specification taken in connection with the drawings which form a part of this application, and in which

Fig. 1 is a vertical sectional elevation somewhat diagrammatic of the machine and mechanism constructed in accordance with the invention;

Fig. 2 is an elevational view taken at right angles to Fig. 1 and partly in section;

Fig. 3 is a detail plan view illustrating driving connections for one of the feed rollers, this view being taken substantially on line 3—3 of Fig. 1;

Fig. 4 is a plan view of the cutter roll and knife for severing the wrapper strip;

Fig. 5 is an enlarged sectional elevation of the cooperating rollers which function to feed the tear strip and wrapper and form a loop in the tear strip to provide an extra length thereof;

Fig. 6 is a sectional elevation illustrating the tear strip cutter in cutting position;

Fig. 7 is a plan view of the H knife for slitting the wrapper;

Fig. 8 is a plan view of the tear strip and wrapper after the tear strip and the slit portions of the wrapper have been pushed into the pocket of the lower roll shown in Fig. 5;

Fig. 9 is a plan view of the wrapper and tear strip before the wrapper has been cut;

Fig. 10 is a plan view of one end of the wrapper with the tear strip projecting therebeyond after the wrapper has been cut;

Fig. 11 is a plan view of the wrapper and tear strip; and

Fig. 12 is a perspective view showing the wrapper in folded position around an article, or in other words, of the complete package.

The invention briefly described consists of a feeding and cutting attachment or mechanism for a wrapping machine. The mechanism comprises tear strip feeding means and wrapper strip feeding means so constructed and arranged that

the tear strip will be moistened or rendered adhesive and will be applied to one surface of the wrapper strip. Prior to the application of the tear strip to the wrapper strip, however, the wrapper strip is slit longitudinally and transversely by a H knife so as to form flaps. The tear strip is then superposed on the wrapper strip and means is provided for forming a loop therein to provide an excess of material which, after the wrapper strip has been severed, extends beyond one end of the wrapper strip. The wrapper strip with the tear strip secured thereto are fed downwardly through cutting means which cuts the wrapper strip in such a manner as to "straddle" the tear strip which has been previously cut to the desired length and projects beyond one end of the wrapper strip.

Further details of the invention will appear from the following description.

In the particular embodiment of the invention illustrated, the wrapping machine is not shown, but at the bottom of Fig. 1 there is illustrated a conveyor chain 20 which has thereon feeding members 21 which feed the articles 22 to be wrapped through the machine.

The invention described and claimed in this application consists of the mechanism which feeds the wrapper and tear strip to the wrapping mechanism. As illustrated in Fig. 1, the tear strip is mounted on a roll T. From the roll T the tear strip 25 is led through a guide 26 around a feed roll 27 and downwardly between the roll 27 and a second feed roll 28. The roll 28, as shown in Figs. 1 and 2, has a portion 29 in its periphery recessed or cut out. When the tear strip is disposed between the cut-out portion 29 and the feed roll 27 no feeding operation takes place.

It is essential for the accurate feed of the tear strip that the peripheral feeding surfaces of the rolls 27 and 28 be correctly determined and for this reason the notch or recess 29 is made of such length to as provide on the rest of the periphery of the feed roll 28 the required peripheral engagement. The roll 27 is carried by pivoted arms 30 and is held in feeding engagement with the roll 28 by means of a spring 31.

The tear strip 25 passes from the feed rolls 27 and 28 over a heater 32 and around an idler 33 carried by a pivoted arm 34 which is actuated in an anticlockwise direction by a spring 35. From the idler 33 the tear strip passes over a wick 36 of a moistener or adhesive applying device which has a reservoir 37, conduit 38 and vertical bore 39 in which the wick 36 is posi-

tioned. If the tear strip is formed of Cellophane or like material, a Cellophane solvent is applied to the tear strip. From the wick 36 the tear strip passes beneath a heating surface 48 of the heater 32. It will be seen, therefore, that the tear strip is preheated prior to the application of the adhesive or solvent thereto and is also heated after the solvent has been applied in order to evaporate any excess before the tear strip is superposed on the wrapper strip.

The wrapper strip 45 is led from a supply roll W beneath an idler 46 and between the idler 46 and a knife roll 47. The knife roll has extending radially from the periphery thereof an H shaped knife shown in plan view in Fig. 7 and having parallel cutting edges 48 and 49 and a transverse cutting edge 50 which at its ends intersects the knife edges 48 and 49. The knife just described thus forms flaps 51 and 52 in the wrapper strip 45, the flaps being formed in such a position that the tear strip when superimposed upon the wrapper strip will be disposed centrally between the edges of the flaps.

The wrapper strip is led upwardly from the idler 46 and around a feed roll 55 which, as shown in detail in Figs. 5 and 6, has a transverse peripheral pocket 56 therein. A roll 57 carried by arms 58 and 59 pivoted on a shaft 60 is disposed above the feed roll 55. The arms 58 and 59 are connected by a bar 61 which is engaged by a spring 62, the spring holding the roll 57 downwardly into coacting relation with the roll 55.

The roll 57 has radially mounted therein a stud 65. The stud 65 is so mounted as to register with the pocket 56, thus as the wrapper strip 45 and the tear strip 25 pass between the rolls 55 and 57 the stud or pin 65 will force the flaps 51 and 52 of the wrapper into the pocket, as shown in Fig. 5 and will also force the tear strip downwardly between the flaps forming a loop in the tear strip.

As the roll 55 rotates in an anticlockwise direction the tear strip will be engaged by a knife 66 carried by a roll 67 mounted on a shaft 68. Fig. 6 illustrates the knife in cutting engagement with the tear strip in back of the loop formed therein.

The wrapper with the tear strip secured thereto then passes downwardly between a pair of feed rolls 78 and 71 which feed the wrapper strip and tear strip downwardly between a rotating knife 72 and a stationary knife 73. The rotating knife is shown in Fig. 4 as carried by a roll 74 and it will be noted that the knife 72 has a gap 75 which straddles the tear strip and the flaps 51 and 52. That part of the wrapper which passes the gap 75 has been cut previously transversely by the edge 50 of the knife on the roll 57 so that a part 76 of the tear strip extends beyond the flap 51. This is shown in Fig. 11 which also shows that the flap 51 at that end of the wrapper also projects beyond the remaining portion of the wrapper, but to a lesser extent than the projection of the tearing strip.

In Fig. 12 the completed package is shown and it will be seen that the end 76 of the tear strip projects beyond the edge of the package and can be easily and readily grasped. Furthermore, when the tear strip is pulled the slits at the edges of the flap 51 facilitate the tearing of the wrapper.

The driving connections and the mounting for 75

the various feed rolls and cutters will now be briefly described.

The main driving shaft shown at 80 in Fig. 1 has mounted thereon a gear 81 which meshes with a gear 82 carried by the shaft 83 on which the cutter 72 is mounted. Shaft 83 has also secured thereto a gear 85 which meshes with a gear 86 carried by an idler shaft 87. Gear 86 also meshes with a gear 88 mounted on a shaft 89 which carries the feed roll 71. Shaft 89 has also secured thereto a gear 90 which meshes with a gear 91 carried by a shaft 92 which in turn carries the feed roll 70. The shaft 92 has eccentric ends 93 and is adapted to swing toward or away from the shaft 89 on the eccentric end portions thereof. However, in order to resiliently hold the roll 70 in feeding engagement with the roll 71 one end of the shaft has an arm 94 secured thereto which is engaged by a spring 95, the spring acting to swing the shaft 92 toward the shaft 89.

The gear 88 on the shaft 89 meshes with a gear 96 on an idler shaft 97. Gear 96 in turn meshes with a gear 98 on a shaft 99 on which the roll 55 is mounted. Gear 98 in turn meshes with a gear 100 carried by the shaft 68 of the knife 66. Gear 100 meshes with a gear 102 mounted on the shaft 60. Gear 102 drives a gear 103 mounted on a shaft 104 which carries the roll 57.

From the showing in Fig. 3 it will be noted that the gear 102 is a wide gear and meshes not only with the gear 103 on shaft 104, but with a gear 105 mounted on the shaft 106 which carries the feed roll 28. Shaft 106 also drives the shaft 109 on which the roll 27 is mounted by the gear 105 which meshes with gear 118 on the shaft 109.

It should be noted that the arms 58 and 59 on which the shaft 104 is mounted are pivoted on the axis of the shaft 60 and since the gear 103 on the shaft 104 meshes with gear 102 on shaft 60, when the arms are swung upwardly to permit the tear strip and web or wrapper strip to be threaded through the machine and between the rolls 55 and 57 the roll 57 will be controlled by the intermeshing gears, thus preventing the stud or pin 65 from being so rotated as to throw the pin out of register with the pocket 56 when the arms are swung downwardly again.

From the foregoing specification it will be seen that the tear strip and wrapper strip will be accurately fed and cut and that by reason of the loop formed in the tear strip an extra length of tear strip is provided so that after the wrapper has been cut an end of the tear strip will project beyond an end of the wrapper, as shown particularly in Fig. 11. Furthermore, by providing slits in the wrapper parallel to the tear strip and at the ends of the wrapper the tearing or severing of the wrapper by the pull on the strip is facilitated.

Although one specific embodiment of the invention has been particularly shown and described, it will be understood that the invention is capable of modification and that changes in the construction and in the arrangement of the various cooperating parts may be made without departing from the spirit and scope of the invention, as expressed in the following claims.

What I claim is:

1. In a machine of the character described, means for cutting a transverse slit in a wrapper strip, means for superimposing a tear strip longitudinally on the wrapper strip across said slit, a feed roll having a transverse pocket in its pe-

riphery, means for bending the tear strip and adjacent parts of the wrapper strip into said pocket, and means for cutting the tear strip and wrapper strip transversely.

2. In a machine of the character described, means for cutting spaced longitudinal slits and an interconnecting transverse slit in a wrapper strip, means for superimposing a tear strip longitudinally on the wrapper strip across said transverse slit, a feed roll having a transverse pocket in its periphery, means for bending the tear strip and adjacent parts of the wrapper strip into said pocket, and means for cutting the tear strip and wrapper strip transversely.

3. In a machine of the character described, means for cutting a transverse slit in a wrapper strip, means for superimposing a tear strip longitudinally on the wrapper strip across said slit, a feed roll having a transverse pocket in its periphery, means for bending the tear strip and adjacent parts of the wrapper strip into said pocket to form a loop in the tear strip, means for severing the tear strip back of said loop, and other means for severing the wrapper strip transversely from the longitudinal slits therein to its edges.

4. In a machine of the character described, means for cutting a transverse slit in a wrapper strip, means for superimposing a tear strip longitudinally on the wrapper strip across said slit, a feed roll having a transverse pocket in its periphery, means for bending the tear strip and adjacent parts of the wrapper strip into said pocket to form a loop in the tear strip, means for severing the tear strip back of said loop, and a knife for severing the wrapper transversely from the longitudinal slits therein to its edges, said knife having a gap therein to straddle the tear strip.

5. In a machine of the character described, means for feeding a wrapper strip, means for making an H cut in said strip with two cuts parallel to the longitudinal edges of the strip and the connecting cut transverse to the strip, means for superposing a tear strip on the wrapper strip

between the parallel cuts, and means for forming a loop in the tear strip opposite the cuts in the wrapper strip.

6. In a machine of the character described, 5 means for feeding a wrapper strip, means for making an H cut in said strip with two cuts parallel to the longitudinal edges of the strip and the connecting cut transverse to the strip, means for superposing a tear strip on the wrapper strip 10 between the parallel cuts, means for forming a loop in the tear strip, and means for cutting the tear strip in back of the loop in the direction of feed of the tear strip opposite the cuts therein.

7. In a machine of the character described, 15 means for cutting spaced longitudinal slits and interconnecting transverse slits in a wrapper strip at longitudinally spaced intervals, means for superimposing a tear strip on the wrapper strip between the longitudinal slits and across the 20 transverse slits, a feed roll having a transverse pocket in its periphery, means for bending the tear strip and adjacent parts of the wrapper strip into said pockets to form loops in the tear strip, means for severing the tear strip back of said loops and other means for severing the wrapper strip transversely on lines longitudinally spaced from the severed ends of the tear strip from the longitudinal slits therein to its edges.

8. In a machine of the character described, 30 means for cutting spaced longitudinal slits and interconnecting transverse slits in a wrapper strip at longitudinally spaced intervals, means for superimposing a tear strip on the wrapper strip between the longitudinal slits and across the 35 transverse slits, means for conditioning the tear strip to adhere to the wrapper strip, a feed roll having a transverse pocket in its periphery, means for bending the tear strip and adjacent parts of the wrapper strip into said pocket to 40 form loops in the tear strip, means for severing the tear strip back of said loops, and a knife for severing the wrapper transversely from the longitudinal slits therein to its edges, said knife having a gap therein to straddle the tear strip.

45 WILHELM B. BRONANDER.
